(57) **CLAIM**

I claim the ornamental design for a trigger guide, as shown and described.

DESCRIPTION

FIG. 1 is a rear perspective view of a trigger guide in accordance with my new design;

FIG. 2 is a front perspective view of the trigger guide of FIG. 1;

FIG. 3 is a right-side elevation view of the trigger guide of FIG. 1;

FIG. 4 is a left-side elevation view of the trigger guide of FIG. 1;

FIG. 5 is a front elevation view of the trigger guide of FIG. 1;

FIG. 6 is a rear elevation view of the trigger guide of FIG. 1;

FIG. 7 is a top plan view of the trigger guide of FIG. 1; and,

FIG. 8 is a bottom plan view of the trigger guide of FIG. 1. The portions of the trigger guide shown in broken lines in the figures depict unclaimed environmental subject matter, are for illustrative purposes only, and form no part of the claimed design. Similarly, unshaded portions that appear between broken lines or beyond boundary in the figures form no part of the claimed design. The dot-dash broken lines depict the boundaries of the claim that form no part thereof.
